MATERIAL DISTRIBUTING RECEPTACLE

George K. Viall, Milwaukee, and Rudolph F. Lindow, Wauwatosa, Wis., assignors to Chain Belt Company, Milwaukee, Wis., a corporation of Wisconsin

Application March 14, 1947, Serial No. 734,653

3 Claims. (Cl. 214—59)

1

The invention relates to mechanism for controlling the discharge doors of traveling material handling receptacles, of which the buckets of the well known "boom and bucket" distributing apparatus widely employed in conjunction with paving concrete mixers for the placement of concrete in road building and street paving operations may furnish a typical example.

The invention has for its principal object the provision of an improved remote control mechanism for such receptacle doors whereby the operator, from a fixed control station, may cause opening and closing of the doors at will, to any desired degree within their limits of movement, and/or may maintain them for any desired time in any position within such limits, all without regard to the position of the receptacle on the boom or other trackway, or of its rate and/or direction of travel thereon.

For purposes of disclosure an application of the principles of the invention to this particular species of material distributing apparatus has been illustrated in the accompanying drawings forming a part of this specification, but it will be clear from the following description that such principles may be readily incorporated into analogous types of apparatus without departing from the spirit of the invention.

In the said drawings:

Figure 1 is a side elevational view, partly broken away, of the discharge end portion of a conventional paving concrete mixer and its associated boom and bucket distributing apparatus, equipped with one form of bucket door control mechanism constructed and arranged in accordance with the invention, the parts being shown in the positions they occupy when the door is closed;

Fig. 2 is a similar view, on a slightly larger scale, illustrating the positions assumed by the parts when the door is fully open;

Fig. 3 is a top plan view;

Fig. 4 is an enlarged sectional-elevational view on the plane indicated by the line 4—4 of Fig. 1, looking in the direction of the arrows; and

Fig. 5 is a sectional-plan view on the plane indicated by the line 5—5 of Fig. 2.

Referring to the said drawings more in detail, the frame 10 of the concrete mixer 11 has a substantially horizontal boom 12 mounted upon it for swinging movements, which boom comprises a pair of oppositely facing transversely spaced channel beams 13 and 14, the lower flanges of which provide trackways for the wheels or rollers 15 of a traveling carriage 16 which supports the material-receiving receptacle or bucket 17. The

bucket is open at its top for the reception of the concrete from the mixer 11, and is provided with a bottom discharge opening 18 controlled by a swinging door 19 which may be swung between the closed position shown in Fig. 1 and the open position shown in Fig. 2 by suitable linkage 20 terminating in a bell-crank lever 21 pivotally mounted at 22 on an upper portion of the bucket. The carriage 16 and bucket 17 are drawn outwardly along the boom 12, i. e. from right to left as viewed in Figs. 1 and 2, by traction means comprising an outward-traverse cable 23, anchored to the bucket carriage at 24 and passing around idler sheaves 25, 26 and 27 to a winding drum 28 mounted on an upper portion of the mixer frame 10 and arranged to be driven in either direction at will from the mixer power plant, through a chain drive 29. The carriage and bucket are drawn inwardly along the boom by an inward-traverse cable 31 which is also attached to the carriage by the anchor 24 and extends therefrom around an idler sheave 32, adjacent the sheave 27, to the winding drum 28, upon which it is wound in a direction opposite to that in which the cable 23 is wound.

The parts thus far described are more or less conventional in this type of apparatus, as are also the controls (not shown) whereby the operator, from his station on the mixing machine, may hold the winding drum stationary and/or cause rotation of it in either direction at will.

The mechanism for enabling the operator to have full control at all times over the movements and position of the bucket door 19 comprises a door-control cable separate from the bucket-traverse cables 23 and 31, which door-control cable has portions 35 and 36 extending in opposite directions from the upper end of the bell-crank lever 21, to which the said cable is secured as by clips 37. From this anchorage the cable portion 35 passes around idler sheaves 38, 39 and 40, journaled on the same shafts as the idlers 25, 26 and 27 respectively, so that at least this part of the door-control cable substantially parallels the corresponding portion of the outward-traverse cable 23. From the sheave 40 the cable portion 35 extends upwardly to and partly around idlers 41 and 42, and thence to a winding drum 43 mounted on the mixer frame 10 adjacent the drum 28. The other door-control cable portion 36 extends from the anchorage 37 to the sheave 45 (Fig. 4) journaled on the same shaft as the sheaves 27, 32 and 40, thence upwardly to and partly around idlers 46 and 47 and to the drum 43, about which it is wound in a direction

opposite to that in which cable 35 is wound. A chain and sprocket drive 48 drives the winding drum 43 from the drum 28, in the same directions and at the same speeds as the latter, and thus the several cables 23, 31, 35 and 36 will all be caused to travel at the same speeds.

The idlers 41 and 46 are floatingly journaled on a shaft 50 mounted in a yoke 51 carried by the piston rod 52 of a double acting reciprocating hydraulic or other fluid-pressure motor 53 mounted on the mixer frame 10. Fluid may be alternately admitted to and exhausted from the opposite ends of the cylinder of such motor through appropriate conduits 54 which extend to the operator's station on the mixing machine, where they are connected with any suitable control valve whereby fluid pressure supply and relief to and from the motor may be effected as desired.

It will be noted that the portion 35 of the door-control cable is trained about the right hand portion of its idler 41, while the companion cable portion 36 is trained about the left hand portion of its idler 46. With the parts in the positions shown in Fig. 1, and with the winding drums 28 and 43 held against rotation whereby the bucket is stationary on the boom, if fluid be admitted to the left hand end of motor cylinder 53 and exhausted from the right hand end thereof, whereby to cause movement of the piston rod 52, yoke 51 and idlers 41 and 46 from the Fig. 1 position toward the Fig. 2 position, the idler 41 will increase the tension on door-control cable 35, while the idler 46 will tend to relieve tension on cable 36. Since the drum 43 in effect serves as an anchor for those portions of the respective cables between such drum and the idlers 41 and 46, the pull thus imposed on the cable 35, in conjunction with the slackening of the tension on cable 36, produces movement of the portions of such cables extending from said idlers to the bucket 17, which cable movement shifts the bell-crank lever 21 from its Fig. 1 position toward or to its Fig. 2 position and through linkage 26 partially or fully opens the door 19. The parts are so proportioned that a full stroke of the piston of the motor 53 will produce full opening of the said door, and obviously if such piston be moved through less than its full stroke the door will be but correspondingly partially opened. When the piston stops movement of the cables 35 and 36, lever 21, linkage 26 and door 19 likewise ceases, and the door will be retained in the position to which it has been moved until the motor 53 is again actuated. If such actuation be in a direction opposite to that above referred to, the idler 46 will increase the tension on cable 36 while the idler 41 will slacken tension on cable 35, with consequent reverse movement of the lower cable portions which will return the lever 21 toward or to its Fig. 1 position, with corresponding closing movement of the bucket door 19.

Obviously, the door control just described may take place with the bucket positioned at any point along the boom, within the limits of its travel thereon; and the door movements may also be effected while the bucket is traveling in either direction on the boom. Thus, if with the door closed as in Fig. 1, the winding drum 28 be operated in such direction as to cause the outward-traverse cable 23 to propel the bucket outwardly on the boom, the synchronously operated winding drum 43 will be moving the door-control cable 35 in the same direction and at the

same speed as the said cable 23, and while the two cables are moving relative to the boom there is no relative movement between them, or between the cable 35 and the bucket, which would shift the lever 21 and produce opening of the door. However, if during such bucket traverse the motor 53 be actuated to retract the yoke 51 and its idlers 41 and 46, the result will be an acceleration of the speed of the lower portion of the door-control cable 35 and a corresponding retardation of the lower portion of the cable 36, producing relative longitudinal movement between such cable portions and the corresponding portions of the traverse cables 23 and 31, which will shift the bell-crank 21 and open the door. Reverse actuation of the motor 53, with the bucket traveling in the same outward direction, will cause acceleration of the cable 36 and retardation of cable 35, with consequent reverse motion of bell-crank lever 21 and closing of the door.

With the bucket traveling inwardly along the boom, actuation of the motor 53 will produce the same results as regards opening and closing of the door. In this case however, retraction of the yoke 51 and its idlers will produce retardation of cable 35 relative to traverse cable 23, and acceleration of cable 36 relative to traverse cable 31, to produce door opening, and of course a reverse action when the yoke is moved outwardly, to secure door closing.

So long as the piston of motor 53 is stationary, whatever its position in its cylinder may be, the door will be maintained in a corresponding position relative to its limits of travel, regardless of whether the bucket be stationary on the boom, or traveling in either direction thereon. On the other hand, actuation of the motor in either direction at any time will produce a corresponding opening or closing movement of the door, in like degree; and thus the operator may have full control over the door at all times and under all operating conditions.

While the traverse cables 23 and 31 have been referred to as separate cables, obviously, like the door-control cable, they may be different portions of a single cable which is attached to the carriage by the anchor 24.

What is claimed is:

1. In apparatus for distributing concrete and the like, the combination of a trackway; a receptacle reciprocatably mounted on said trackway and having a discharge-controlling door movable to and from a closed position; a receptacle-traversing cable extending along the trackway and connected to the receptacle; means for moving said cable in either direction along the trackway at will, to traverse the receptacle thereon; a separate door-control cable having a portion extending along the trackway; connections between the receptacle door and said portion of the door-control cable, operable through relative movements between the two cables to move said door from and to its closed position; means for moving said door-control cable in synchronism with the receptacle-traversing cable, whereby to normally prevent actuation of said door operating means and thus maintain the door in a determined position; and mechanism movable to volitionally variable extents and acting upon the door-control cable while so moving to differentiate the rates of movement of the two cables regardless of the direction and rate of movement of the traversing cable, whereby to actuate said door operating

connections and move the door to an extent corresponding to the extent of operation of said mechanism.

2. In apparatus for distributing concrete and the like, the combination of a trackway; a receptacle mounted on said trackway for reciprocation thereon, said receptacle having a door for controlling discharge of material therefrom; a receptacle traversing cable having outward-traverse and inward-traverse portions connected to the receptacle and extending along the trackway; a winding drum for driving said cable; a separate door-control cable substantially paralleling said traversing cable along said trackway; connections between said door-control cable and the receptacle door, operable through relative movement between the two cables to move said door; a winding drum for said door-control cable; means for operating the two winding drums in synchronism whereby to move corresponding portions of the two cables in like directions at equal speeds and thus normally prevent actuation of said door operating connections and maintain the door in a given position; and means engageable with said door-control cable and operable at will to temporarily accelerate and decelerate portions of such cable adjacent the door operating connections, with resultant actuation of the latter and shifting of the door to a different position.

3. In concrete distributing apparatus for a mixing machine having a frame, the combination of a boom carried by said mixer frame; a receptacle mounted for reciprocation on the boom and having a discharge controlling door; a pair of winding drums mounted on said mixer

frame; a traversing cable connected to the receptacle and having outward-traverse and inward-traverse portions extending along the boom and to one of said winding drums; a separate door-control cable substantially paralleling said traversing cable along the boom and extending to the other of winding drums; door operating mechanism connected to said control cable, operable through differential movement of the two cables; means for operating said winding drums in unison whereby to move complementary portions of the two cables in like directions at equal speeds, thus normally preserving a determined relationship between them which prevents actuation of said door operating mechanism and maintains the door in a given position; and a reversible motor on the mixer frame having means engaging the door-control cable, said motor being operable at the volition of the operator to temporarily increase or decrease the speed of portions of said door-control cable adjacent the door operating mechanism, with resultant actuation of the latter and shifting of the door to a different position.
